(57) **CLAIM**

The ornamental design for a laser delivery device, as shown and described.

DESCRIPTION

FIG. 1 is a perspective view of a laser delivery device showing our new design;

FIG. 2 is another perspective view thereof;

FIG. 3 is a front elevation view thereof; and,

FIG. 4 is a left elevation view thereof; due to symmetry about a longitudinal axis, each of the right elevation and bottom plan views is a mirror image of the present view, as flipped across the vertical axis, and the top plan view is identical to the present view.
